Primary Examiner — Dana K Weiland*Assistant Examiner* — Jennylo M Binas(74) *Attorney, Agent, or Firm* — Gabriel A. Haboubi(57) **CLAIM**

The ornamental design for a portable vacuum, as shown and described.

DESCRIPTION

FIG. 1 is a top perspective view of a portable vacuum showing our new design.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof; and,

FIG. 8 is a bottom perspective view thereof.

Features of the portable vacuum shown in broken line form no part of the claimed design.

1 Claim, 8 Drawing Sheets(56)
